UNITED STATES PATENT OFFICE.

WALTER M. REASON, OF PONTIAC, MICHIGAN.

INNER TUBE.

1,109,939.

Specification of Letters Patent. Patented Sept. 8, 1914.

Application filed January 15, 1914. Serial No. 812,211.

To all whom it may concern:

Be it known that I, WALTER M. REASON, citizen of the United States, residing at Pontiac, county of Oakland, State of Michigan, have invented a certain new and useful improvement in Inner Tubes, and declare the following to be a full, clear, and exact description of the same, such as will enable others skilled in the art to which it pertains to make and use the same, reference being had to the accompanying drawings, which form a part of this specification.

My invention relates to inner air tubes for pneumatic tires of the so-called double type in which an outer casing held firmly upon the wheel is made air-tight by an inner air-tight tube that conforms to the inner shape of the casing, and it consists in the construction, combination and arrangement hereinafter described in the specification and pointed out in the claims.

In the drawings: Figure 1, is a cross section of casing in dotted lines, inclosing a cross section of one form of my improved inner tube in full lines as arranged when in service. Fig. 2, is a vertical elevation of the inner tube as inflated sufficiently to give it a rounder contour. Figs. 3 and 4 are detached cross sectional views of modifications 30 of the joint between the sections of the tube as hereinafter described.

Similar letters refer to similar parts.

A, represents a cross section in dotted lines of the casing.

B, represents cross section of the inner tube inflated with reference to the casing A. It is immaterial whether the casing is of the clincher type or of the straight type for detachable rims as my invention is applicable to all types of casings which require inner tubes to make them air-tight when in use.

C, represents that portion of the tube casing which is adjacent to the rim or what may be termed the rim side of the tube.

D, represents that portion of the tube which is adjacent to the tread side of the casing and which therefore may be termed the tread side or tread of the tubes. These two sides are joined at E, F so that substantially circumferentially the joint is about one-half of the distance between the extreme of the tread side and the rim side of the tube.

In Figs. 3 and 4 I have shown a tube 55 made up. In Fig. 3 one-ply merely, as hereinafter explained, designated D', C' with

a joint at E'; in Fig. 4, I have represented a two-ply tube, made up of two layers marked C², C³, and D², D³ with joint at E². This gives a stronger tube and better joint as will be hereinafter explained, than the forms shown in Fig. 1 with a one-ply d on the rim side and a two-ply as d, d' on the tread side. Fig. 2, shows a portion of the tube cut away so as to show the inside of 65 the inner or rim half and the outer or tread half and especially the circumferential joint joining the two halves on the opposite side looking inwardly. In this respect it will apply to any form of compound 70 tube of one-ply or two-ply as shown and described, the joint being shown at E³.

In order to make this improved tube I use a fine heavy fabric impregnated with rubber and woven in the usual form to allow elasticity in one direction only and to be substantially inelastic in the opposite direction. The rim or circumferential inner side of the tube is made of this elastic fabric so arranged as to be elastic circumferentially 80 of the section of the tube; in other words, at substantially right angles to the plane of the tube, or of the wheel upon which it is applied.

The tread or circumferential outer side of the tube is made of the same fabric but arranged so as to be elastic circumferentially or in a line corresponding with the plane of the rim of the wheel to which the tube is applied and substantially non-elastic at 90 right angles to the plane of the tube. This fabric by reason of the rubber is not only elastic as stated but is air-tight and the two parts are joined together and cemented upon each side of the tube circumferentially as 95 shown at E, E¹, E², they being united firmly and vulcanized together with vulcanizing cement so that the joint is air-tight. By this means I manufacture a tube which is only expandible or elastic in cross section 100 for a section on the rim side of the tube (which is the inner side circumferentially of the tube) but is non-elastic circumferentially while the outer or tread side of the tube is elastic circumferentially of the tube, 105 that is to say, around the wheel, but is not elastic in cross section, and it is in this feature as introduced and made valuable in a tube of the type described that my invention consists. By this means I am enabled 110 to make a tube which is sufficiently elastic in all directions to accommodate it when

under air pressure, to the casing for which it is designed, even to the extent of enlarging in diameter of its plane upon the tread side, and also enlarging in cross section by the 5 cross elasticity of the rim side, so that the small amount of the entire elasticity required is fully met. At the same time I am enabled to make a practical tube that shall be sufficiently air-tight, as well as elastic as 10 stated, but above all shall be composed of a compound of elastic material and a fabric instead of being made up entirely of pure vulcanized rubber as is the usual practice.

It is evident that in a tube of fibrous material or fabric without providing means for 15 its compensating under air strains or air pressures that if the fabric is non-elastic circumferentially of the wheel an enormous strain would be thrown upon a portion of 20 the tube adjacent to the tread in order to enlarge in its general diameter and adequately fill the space in the casing; on the other hand, if it is only made elastically extendible circumferentially of the wheel it will 25 not be elastic in cross section and the whole bursting strain of the air pressure would be thrown upon the cross sectional diameter of the tube proper and it would have to be made extremely strong in order to stand 30 this pressure which would not be transferred to the casing. On the other hand, by making the tube one-part of which is elastic in one direction and the other part elastic in the other direction, as stated, I avoid these 35 difficulties. It is essential, however, that the elasticity of the rim or wheel side of the tube shall be in line of the cross section of the tube proper and that the elasticity of the tread side of the tube shall be circumferential 40 of the casing, because it is the larger cir-

cumference of the outer part that requires to be accommodated by the longitudinal expansibility enlargement.

The mode of operation of this device when employed is sufficiently obvious without any 45 further description.

It is obvious that the ends of the fabric when brought into circumferential arrangement can be united and made properly air-tight by vulcanizing the same as the side 50 joints are so made in order to form a complete air-tight tube with the usual valves and valve-stems being inserted therein in the usual form, all of which is unnecessary to illustrate or describe. 55

Having thus described my invention what I desire to claim is:

1. As a new article of manufacture, an inner tube for double tube pneumatic tires consisting of a rim side elastic solely on the 60 line of the cross section and an outer tread side joined thereto and elastic solely longitudinally and means for uniting the two sections to form an air-tight joint, substantially as described. 65

2. As a new article of manufacture, an inner tube for double tube pneumatic tires constructed with the larger circumferential part of said tube elastic circumferentially but non-elastic in cross section, and the inner, or smaller, circumferential part non-elastic circumferentially but elastic in cross section, substantially as described. 70

In testimony whereof, I sign this specification in the presence of two witnesses.

WALTER M. REASON.
